[57] **CLAIM**

The ornamental design for a roadside mail box protector, as shown and described.

DESCRIPTION

FIG. 1 is a perspective view of a roadside mail box protector showing my new design, the mail box being shown in phantom lines;

FIG. 2 is a top plan view of the roadside mail box protector;

FIG. 3 is a right side view of the roadside mail box protector;

FIG. 4 is a front view of the mail box protector;

FIG. 5 is a rear view of the mail box protector;

FIG. 6 is a left side view; and,

FIG. 7 is a bottom view thereof.

The broken line showing of a mailbox and post in FIG. 1 is for illustrative purposes only and forms no part of the claimed design.
